ATION OF ILLINOIS

COIN CONTROLLED MECHANISM

Application filed October 22, 1930. Serial No. 490,364.

This invention relates to improvements in check or coin controlled mechanism, and one of the objects of the same is to provide an improved device of this character which will receive a coin or check of a predetermined denomination and permit the same to move into an operative position with respect to the coin actuated mechanism, but will arrest improper checks and prevent the same from actuating the mechanism, which it is necessary to actuate by the coin or check.

A further object is to provide an improved device of this character embodying a driven element adapted to be set in motion by the coin controlled mechanism, and improved means for rendering the driven element active and inactive with respect to the coin controlled mechanism, whereby the driven element will not be actuated until a proper check or coin is inserted.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a view taken on line 1—1, Figure 2.

Figure 2 is a vertical sectional view taken on line 2—2, Figure 1.

Figure 3 is an irregular sectional view taken on line 3—3, Figure 2.

Figure 4 is a detail perspective view of a controlling member.

Figure 5 is a detail perspective view of one of the members by means of which the driven element is actuated.

Figure 6 is a view similar to Figure 1, showing the parts in a different position.

Figure 7 is a view similar to Figure 6, with parts omitted.

Figures 8 and 9 are detail views partly in elevation and partly in section of the check carrier, showing the same in different positions.

Referring more particularly to the drawings the numeral 10 designates a check or

coin carrier which is preferably in the form of a disc having a check seat 11 and which is provided with a shoulder 12 on its periphery, adapted to engage a shoulder 13 on the supporting frame to limit the rotary movement of the check carrier 10 in one direction. The check carrier is connected through the medium of a shaft 14 with an operating handle 15, and by means of which latter a forward and backward movement may be imparted to the check carrier.

The check carrier is provided with a recess 16 opening through its periphery, for a purpose to be hereinafter set forth.

Suitably mounted is a check detector element 17 which is provided with a portion 18 adjacent one end adapted to enter the recess 16 in the check carrier when the latter assumes the position shown in dotted lines in Figure 1. A spring 19 tends normally to move the end 15 in a direction that it will enter the check seat 11 in the check carrier when there is no check in the seat or when a check which is thinner than the predetermined size of a check, is inserted in the check seat.

Carried by the member 17 is a projection 20 which enters the check seat under the conditions just recited, to permit the portion 18 to enter the recess 16 in the carrier 10. When, however, a proper check is placed in the check seat the projection 20 on the detector member 17 will be engaged by the check or coin and the end 18 will be held so that it will not enter the recess 16, thereby permitting the check carrier to be inverted to the position shown in Figure 9 to discharge the check therefrom.

All of the above referred to parts are of the ordinary and well known construction.

In the present form of the invention the check controlled mechanism is shown in connection with a driven member 21, and the latter is supported in a suitable bearing 22 so that the extremity 23 of the member 21 will enter a recess 24 in a rotatable member 25 which has a constant direction of rotation. This member 25 is mounted independently of the check carrier 10 and is provided with notches or recesses 26 opening through its

periphery and is also provided with a portion 27 which is of a diameter considerably less than the diameter of the portion 25. In the reduced portion 27 is provided notches or recesses 28 opening through the periphery thereof, and the notches 28 are preferably disposed in proximity to the respective notches 26.

5 The driven member 21 being connected with the member 25—27, will be rotated when the latter is rotated and will be prevented from rotation when the member 25—27 is locked against rotation.

10 Pivotedly mounted upon a suitable supporting structure is a dog 29 which is provided with a portion 30 adapted to enter the recesses 26 in the member 25. The dog 29 is mounted to swing about a pivot 31 and is provided with a laterally deflected portion 32 15 which co-operates with a check receiving seat 33 arranged adjacent the path of movement 20 of the periphery of the check carrier 10.

A spring 34 tends normally to move the dog 27 in a direction that the end 30 thereof 25 will enter one of the recesses 26 when the latter is in proximity thereto.

When a check 35 is deposited upon the support 33, it will be held between the portion 32 of the dog 29 and the support 33 until the 30 direction of rotation of the check carrier 10 is reversed, at which time the shoulder 12 will engage the periphery of the check and force the same between the space formed by the portion 32 of the dog 29 and the support 33. This will result in rocking the dog 29 about its pivot against the stress of the spring 34 to withdraw the portion 30 of the dog 29 35 out of the recess 26, thereby releasing the member 25 so that it will be rotated by the handle 15 and with it the driven element 21.

40 A control member 36 is pivotally mounted as at 37 and comprises two arms 38—39, preferably separated from each other. The extremity 40 of the portion 38 is shaped to form a track or guide for supporting and actuating the dog or pawl to maintain the same under predetermined conditions, in a position that it will not enter one of the recesses 28 in the portion 27 of the member 25. When, however, the member 36 is shifted to lower the portion 40 of the arm 38 the locking dog or pawl will be allowed to enter one of the recesses 28. This is accomplished in the following manner.

45 An actuating dog 41 is pivotally mounted as at 42 to an oscillatable member 43. This dog is provided with an extremity 44 and a laterally projecting pin 45 in proximity to such extremity. The dog 41 and the control member 36 are laterally spaced from each other so that the operation of one will not interfere with the operation of the other. A spring 46 tends normally to move the member 43 in one direction, and the member 43 is 50 connected with the handle 15.

The arm 39 of the member 36 is provided with a bifurcated portion 46 into which the end 30 of the locking dog 29 projects and operates.

55 The normal position of the parts are as shown in Figure 6, that is with the locking dog 29 raised by the spring 34 so that its end 30 will enter one of the recesses 26 and with the control member 36 in a position that the portion 40 thereof will be raised so that when the member 43 is oscillated by the handle 15 and a proper check or coin deposited into the check seat 11 in the carrier 10, the pin or projection 45 on the dog 41 will ride upon the portion 40 of the member 36. The member 36 is held in this position through the medium of the spring 34, the locking dog 29 and the extremity 30, which latter operates in the bifurcation 46 in the arm 39 of the member 36.

80 When a proper check or coin is deposited in the check seat 11 and the latter has been turned to the position shown in Figure 9, upon the release of the handle 15 or the turning of the same in the opposite direction, the check 35 will, in the manner already set forth, rock the dog 29 to move its end 30 out of the recess 26, thereby releasing the member 25—27 for rotary movement with the handle 15. As the locking dog 29 is thus lowered the end 30 operating in the bifurcation 46 will rock the member 36 about its pivot to lower the arm 38 and portion 40 of the control member 36 to the position shown in Figure 1. This will permit the operating dog 41 to be lowered so that the end 44 thereof will enter one of the recesses 28 in the portion 27 of the member 25, so that when the handle 15 is moved in the opposite direction, carrying with it the member 43 and dog 41, the member 25—27 will be rotated and consequently the driven element 21.

90 As soon as the check 35 has passed through the space between the portion 32 of the locking dog 29 and the support 33, the spring 34 will rock the locking dog 29 about its pivot so as to again move the projection 30 into one of the notches 28. This movement will also rock the control member 36 about its pivot, causing the portion 40 and the arm 38 to move from the position shown in Figure 8 to the position shown in Figure 6, and thereby elevate the active end of the dog 41, so that upon oscillation of the handle 15, the member 25—27 will not be rotated and the driven element 21 will remain idle.

100 The driven element 21 in the present form of the invention, is shown as constituting a shaft carrying a sprocket wheel 47 which operates upon a sprocket chain 48, and this chain is connected to an arm 49 of a rock shaft 50, the portion 51 of which latter is provided with a deflected extremity 52 adapted to be moved into the path of movement of the check 35, out of the check carrier 10, and thereby prevent the check 35 from dropping

out of the seat 11. The means for retaining the check 35 in the seat, however, constitutes no portion of the present invention, but constitutes a portion of the subject matter of our application Serial Number 483,863, filed September 23, 1930.

While the preferred form of the invention has been herein shown and described, it is to be understood that various changes may be made in the details of construction and in the combination and arrangement of the several parts, within the scope of the claims, without departing from the spirit of this invention.

What is claimed as new is:

1. Check controlled mechanism embodying a check carrier movable forwardly and backwardly, an actuating member having a constant direction of movement, a dog connected with the check carrier for forward and backward bodily movement therewith, said dog operating to move the said actuating member upon each movement of the dog in one direction, a locking member for the said actuating member, means whereby said locking member will be actuated through a proper inserted check to render the locking member inactive, and means responsive to the movement of the locking member as it is being rendered inactive, for maintaining the said actuating member against operation by said dog.

2. Check controlled mechanism embodying a check carrier having a forward and backward movement, a driven member having a constant direction of movement, a dog movable with the check carrier and with respect thereto for moving said driven member upon each bodily movement of the dog in one direction, means for locking said driven member against operation, a controlling member for causing the dog to be rendered active and inactive with respect to said driven member, means controlled by an inserted check for rendering the locking member inactive, and means for automatically operating the said controlling member to render the said dog active and inactive with respect to the said driven member.

3. Check controlled mechanism embodying a check carrier having a forward and backward movement, a driven member having a constant direction of movement, a dog movable with the check carrier and with respect thereto for moving said driven member upon each bodily movement of the dog in one direction, means for locking said driven member against operation, a controlling member for causing the dog to be rendered active and inactive with respect to said driven member, means controlled by an inserted check for rendering the locking member inactive, and means whereby the movement of said locking member into inactive and active positions will correspondingly render the said dog active and inactive with respect to said driven member.

4. Check controlled mechanism embodying a check carrier movable forwardly and backwardly, a driven member having a constant direction of movement, a dog movable with and with respect to said check carrier and co-operating with said driven member to move the latter, a locking member for the driven member, means controlled by an inserted check for rendering the locking member inactive, and a controlling member for rendering the dog active and inactive with respect to the driven member, said controlling member being responsive in its operation to the operation of said locking member.

5. Check controlled mechanism embodying a check carrier movable forwardly and backwardly, a driven member having a constant direction of movement, a dog movable with and with respect to said check carrier and co-operating with said driven member to move the latter, a locking member for the driven member, means controlled by an inserted check for rendering the locking member inactive, a controlling member for rendering the dog active and inactive with respect to the driven member, and interengaging means between said locking member and said controlling member whereby the operation of the latter will be controlled by the operation of the former.

6. Check controlled mechanism embodying a check carrier oscillatable forwardly and backwardly, a driven member having a constant direction of rotation, means connected with the check carrier and co-operating with said driven member for actuating the latter, a locking element for the driven member, a pivotally mounted controlling member, and means controlled by an inserted check for rendering the locking means inactive whereby the movement of said locking member into an inactive position will move the said controlling member about its pivot into an inactive position with respect to the first said means and the movement of the locking member into an active position will cause the controlling member to render the said dog inactive with respect to the said driven member.

7. Check controlled mechanism embodying a driving member having forward and backward oscillating movements, a driven member having a constant direction of rotation, an operative connection between said driving and said driven members, locking means for maintaining said driven member against operation, means whereby said locking member will be rendered inactive by an inserted check, and a pivotally mounted controlling member for rendering said connection active and inactive, said controlling member being responsive in its operation to the operation of said locking member.

8. Check controlled mechanism embodying a driving member having forward and backward oscillating movements, a driven mem-

ber having a constant direction of rotation, an operative connection between said driving and said driven members, locking means for maintaining said driven member against 5 operation, means whereby said locking member will be rendered inactive by an inserted check, a pivotally mounted controlling member for rendering said connection active and inactive, and an interengaging connection between said locking means and said controlling member, whereby the operation of the former will render the latter active and inactive with respect to the first said connection.

15 9. Check controlled mechanism embodying a driving member having forwardly and backwardly oscillating movements, a driven member having a constant direction of rotary movement and provided with peripheral recesses, a locking member for said driven member, a dog connected with said driving member for bodily movement therewith and movement with respect thereto, said dog adapted to enter said recesses to 25 rotate said driven member upon oscillation of said driving member, a pivotally mounted controlling member for causing said dog to be rendered active and inactive with respect to said driven member, means tending normally to position the controlling member to 30 render the dog inactive with respect to the driven member, and means whereby upon the insertion of a proper check the said locking member will be actuated to shift the 35 controlling member to permit the said dog to become active to move the said driven member.

10 10. Check controlled mechanism embodying an oscillatory check carrier, a driven element having a constant direction of rotation, a dog oscillatable in response to the oscillation of the check carrier, said dog operating during its movement in one direction to impart a step of rotation to the driven element, a locking member for the driven element, a control member, and means tending normally to position the control member to render the said dog inactive with respect to the driven member, a locking member for the said driven member, and means whereby upon the insertion of a check the said locking member will be shifted to render it and the said control member inactive to permit the said dog to become active with respect to the driven member.

11 11. Check controlled mechanism embodying an oscillatory check carrier, a driven element having a constant direction of rotation, a dog oscillatable in response to the oscillation of the check carrier, said dog operating during its movement in one direction to impart a step of rotation to the driven element, a locking member for the driven element, a control member, means tending normally to position the control member to ren-

der the said dog inactive with respect to the driven member, means controlled by an inserted check for rendering the locking member inactive, and means whereby the control member will be responsive in its action to 70 the action of said locking member.

12. Check controlled mechanism embodying an oscillatory check carrier, a driven element having a constant direction of rotation, a dog oscillatable in response to the 75 oscillation of the check carrier, said dog operating during its movement in one direction to impart a step of rotation to the driven element, a locking member for the driven element, means controlled by an inserted 80 check for rendering the locking means inactive, a pivotally mounted control member, and interengaging means between the locking member and the control member whereby the operation of the former will control 85 the operation of the latter to render the said dog active and inactive with respect to the driven member.

In testimony whereof we have signed our names to this specification on this 17th day 90 of October, A. D. 1930.

ALFRED D. ANTOINE.
ALBERT E. GEBERT.
